[57] **CLAIM**

The ornamental design for an electric dry shaver with cover, as shown and described.

DESCRIPTION

FIG. 1 is a front elevational view of an electric dry shaver with cover showing my new design with the cover in place, the rear elevational view being identical; FIG. 2 is a left-side elevational view of FIG. 1, the right-side elevational view being identical;

FIG. 3 is a top plan view of FIG. 1;

FIG. 4 is a bottom plan view of FIG. 1;

FIG. 5 is a front elevational view similar to FIG. 1 with a cover removed from the shaver, the rear elevational view being identical;

FIG. 6 is a left-side elevational view of FIG. 5, the right-side elevational view being identical;

FIG. 7 is a top plan view of FIG. 5;

FIG. 8 is a front elevational view of the cover, the rear elevational view being identical;

FIG. 9 is a left-side elevational view of FIG. 8, the right-side elevational view being identical; and

FIG. 10 is a bottom plan view of FIG. 8.
